ATTORNEY

UNITED STATES PATENT OFFICE.

THOMAS L. SWEARINGEN, OF DANVILLE, KENTUCKY.

AUTOMATIC LOCK.

Application filed November 19, 1927. Serial No. 234,497.

This invention relates to a lock for angle cocks in the air line of railroad trains, the general object of the invention being to provide means for locking the cocks in open position as long as the air is in the line, thus preventing unauthorized persons from closing the cocks.

This invention also consists in certain other features of construction and in the combination and arrangement of the several parts, to be hereinafter fully described, illustrated in the accompanying drawings and specifically pointed out in the appended claim.

15 In describing my invention in detail, reference will be had to the accompanying drawings wherein like characters denote like or corresponding parts throughout the several views, and in which:—

20 Figure 1 is a sectional view through a part of an air line, at a junction of the valve casting with the line.

Figure 2 is a section on line 2—2 of Figure 1.

25 Figure 3 is a section on line 3—3 of Figure 2.

Figure 4 is a horizontal sectional view showing the lock in locking position.

30 Figure 5 is a view showing the lock in unlocking position.

In carrying out my invention, I arrange a cylinder 1 in an extension 2 of the valve casing A of the valve, the plug of which is shown at B. The outer end of the extension 35 2 has a cap 4 threaded thereon which closes the end of the cylinder and one wall of the extension has a passage 5 therein which is always in communication with the outer end of the cylinder and which will be connected with the interior of the air line by a port 5' when the plug B is in open position, as clearly shown in Figure 2. A keeper recess 6 is made in the plug and is adapted to be engaged by the stem 7 of a plunger 40 passing through a hole in the casing A into the cylinder 1. The piston part of the plunger is shown at 8 and a coil spring 9 on the stem between the piston part and the bottom of the cylinder 1 tends to hold the parts in unlocking position, as shown in Figure 5. When air enters the line, some of it will pass through the port 5' and passage 5 into the outer end of the cylinder 1, thus acting on the piston and when the air pressure becomes greater than the pressure of spring 9, 55 the piston will be moved inwardly and thus

the end of the stem 7 will engage the keeper 6 and lock the plug B against turning movement. When the air pressure in the line decreases to a point where the spring 9 is 60 stronger than the air pressure, the plunger will be returned to its inoperative position so that the plug can be turned.

A bleed port 10 is formed in the cylinder 1 adjacent its bottom so as to permit air 65 to pass into and out of the cylinder as the piston moves in one direction or the other and this port also prevents air from accumulating in the cylinder 1 as it leaks past the piston which would act to counterbalance 70 the air on the other side of the piston and thus render the device inoperative. The air escaping through the port 10, as it leaks past the piston, will act as a warning to the trainmen that the piston is leaking. 75

It is thought from the foregoing description that the advantages and novel features of my invention will be readily apparent.

I desire it to be understood that I may make changes in the construction and in the combination and arrangement of the several parts, provided that such changes fall within the scope of the appended claim. 80

What I claim is:—

In combination with a valve of an air line 85 system including a valve casing and a rotary member therein, a lateral extension on the valve casing having a cylinder forming chamber in its outer part and an opening in its inner part connecting the chamber with the interior of the casing, the rotary member of the valve having a keeper recess therein and a small port and the valve casing and the extension having a passage therein for connecting the outer end of the chamber with 90 the port when the rotary member is in open position, a piston in the chamber, a stem connected with the piston and passing through the opening to engage the keeper recess when the rotary member of the valve is in open position, a spring engaging the piston for normally holding the stem out of engagement with the keeper recess and a cap threaded on the outer end of the extension and closing the chamber, a portion of the cap being 95 spaced from a part of the extension, said space connecting the outer end of the passage with the outer end of the chamber. 100

In testimony whereof I affix my signature.

THOMAS L. SWEARINGEN.
